FREDERICK KOHNLE, OF DAYTON, OHIO, ASSIGNOR TO THE MONARCH MARKING SYSTEM COMPANY, OF DAYTON, OHIO, A CORPORATION OF OHIO

PRICE TAG

Application filed February 20, 1929. Serial No. 341,442.

This invention relates to improvements in pin tickets of the staple fastener type in which the prongs of the staple provide round pointed double shank pins formed by doubling the wire back on itself, producing a smooth blunt point. The present invention is primarily directed to the structure of the head of the pins or staple to firmly hold the same to the ticket and embed or anchor the free ends of the wire within the ticket or between the plies thereof so that only the pins or shank portions thereof are exposed, leaving nothing to prick the operator or the goods to cause injury, and at the same time substantially sustaining the pins in a perpendicular position from the ticket, adapting the tickets to be easily guided and fed through price marking machines for ticket price marking.

It is, therefore, an object of the invention to provide a pin ticket with a plurality of pins extending from one side with the base portion of the pins embedded within the body or plies of the ticket.

It is another object of my invention to provide a pin ticket with a plurality of round pointed double shank pins formed of a single piece of wire, with the ends of the wire embedded and enclosed within the body of the ticket or between the plies thereof.

Another object of my invention is to provide a pin ticket with one or a plurality of pins extending perpendicularly from one side of the ticket, suitably anchored within the body of the ticket or plies thereof, unexposing any cut ends of the wire forming the pins.

Other advantages and features of the invention will be more fully set forth in the description of the accompanying drawings, in which:

Figure 1 is a perspective view of a plurality of tickets united in gang and defined by transverse notches extending inwardly from one end of the strip containing the improved form of pins or staples.

Figure 2 is a view similar to Figure 1, of a single ticket.

Figure 3 is a detail perspective view of the staple alone.

Figure 4 is a modified form of the staple shown in Figure 3.

The tickets as illustrated are primarily of plural ply material formed by folding upon itself a strip of paper stock, thereby presenting a folded edge for the head end of the ticket, at which end the staple is preferably secured. The folded edge adds reinforcement to the ticket and facilitates the manufacture of the ticket and application of the staples to the ticket to bring the head or cross bar of the staple between the plies of the ticket, and in particular the opposite cut ends of the wire from which the pins or staple are formed, so as to present only the prongs or shank portions of the fastener from one side of the ticket.

The layers or plies of the ticket are adhesively secured together, therefore substantially anchoring the head or cross bar portion of the pins or staple within the body portion of the ticket or between the plies thereof, making it possible to sustain the pins in a perpendicular position from the ticket, which is of advantage in feeding the ticket or gang strip guidingly through a price marking machine, with the points free from interference to feeding progress of the tag or strip for rapidly machine price marking the tickets.

With the staples anchored within the body portion of the ticket or between the plies thereof, the pins are securely and firmly connected to the tickets and no sharp points or cut ends are exposed, and the tickets are capable of being firmly fixed to the fabric or merchandise with ease and without pricking the operator or injuring what is marked.

Referring to the drawings, 1 indicates a gang strip constituting a plurality of price marking tickets integrally joined together, the tickets individually being defined one from the other by transverse notches 2 extending inwardly from one longitudinal edge 25 of the ticket. The notches are utilized to present shoulders for engagement by a feed finger of a price marking machine when the tickets are machine price marked, and also provide for a partial severance of the tags 100

from the strip, facilitating the cutting operation.

The tags or tickets are illustrated as of double-ply thickness formed by folding a strip of paper upon itself and adhesively securing the plies together. In the present instance, the ticket is of double-ply thickness, although the number of plies could be increased, if desired.

Each ticket is provided with a staple furnishing a pair of round pointed double shank pins 3-3 formed of a single piece of wire, each pin formed by bending or doubling the wire back on itself, producing a smooth blunt or rounded point.

The end portions 5-5 of the wire, contiguous with a strand of each of the double wire pins, are bent at right angles to the pin to constitute a bend embedded within the texture of the ticket or between the plies thereof. In the particular arrangement, these bends or end portions 5-5 extend longitudinally of the ticket and toward the folded edge thereof. The second strands of the shanks are joined by a cross bar portion 6 at right angles to the end portions or limbs 5 and also at right angles to the shanks, extending crosswise of the ticket parallel with the upper edge and between the plies thereof.

Thus, the head portions of the staple or pins are completely embedded and hidden within the body portion of the tag or plies thereof, substantially supporting the shanks in an erect or perpendicular position and substantially anchoring the pins or staple to the tag material, so that the tag can be firmly attached to the goods or merchandise ticketed, with no protruding ends or sharp points with burrs or roughened edges exposed to cause injury to the user or to the goods.

In the form of staple shown in Figure 4, the cross or bend portion 6 connecting the shanks or pins is in the form of a U-bend which of itself will provide a base for the pins to sustain the same in a perpendicular position to the plane of the ticket. In the particular bend disclosed, intermediate portions 7-7 of the wire extend parallel with the wire end bends, adding stability and increased surface area, more securely embedding the base portion within the texture of the ticket or between the plies thereof.

When the ticket is applied to the goods, there is no exposure of any part of the staple from the face side of the ticket, leaving the full face available for printing or marking, increasing its utility and attractiveness.

Having described my invention, I claim:

In a pin ticket, a ticket of plural ply thickness the material forming the ticket folded upon itself providing a fold edge along one end of the ticket, and a penetrating and attaching member therefor constituting a wire bent to form a plurality of double shank

pins extending from one side of the ticket, a cross bar portion connecting the pins between the plies of the ticket and extending parallel with and in proximity with the fold edge of the ticket, and the free ends of the wire each respectively extending from the pin at right angles to the cross bar portion and between the plies of the ticket, and toward the fold edge thereof, the cross bar portion and free ends forming a base for the pins and concealed within the ticket.

In witness whereof, I hereunto subscribe my name.

FREDERICK KOHNLE.
